(57) **CLAIM**

The ornamental design for a single feeding basin for pets, as shown and described.

DESCRIPTION

FIG. 1 is a view top plan view of a single feeding basin for pets, showing my new design;

FIG. 2 is a side elevation view thereof;

FIG. 3 is a top perspective view thereof;

FIG. 4 is another top perspective thereof, but shown with environmental structure; and,

FIG. 5 is another perspective view of FIG. 4.

The broken lines illustrate environmental structure that form no part of the claimed design.
